WALL CONNECTION FOR COLLAPSIBLE CONTAINER

Filed Feb. 28, 1942

UNITED STATES PATENT OFFICE

2,372,806

WALL CONNECTION FOR COLLAPSIBLE CONTAINERS

Philip Zalkind, New York, N. Y.

Application February 28, 1942, Serial No. 432,770

3 Claims. (Cl. 217—69)

This invention is a continuation in part of my application, Ser. No. 21,411, filed May 14, 1935, now Patent No. 2,274,765, issued March 3, 1942, and relates to containers and, more particularly, to a formation and arrangement of sheets or panels in such a manner as to facilitate the construction of collapsible containers.

Heretofore, in the construction and formation of collapsible containers, particularly those casting and drawer combinations which were intended to be used, when set up, as file cabinets, the emphasis has been upon the use of corrugated board for the main body construction, that material being the most economical.

Knock-down containers made of wood and metal, are known. These, however, comprise separate members to be assembled and put together by screws, bolts, nails, etc., and are not integrated assembled units.

The present invention provides means and methods for substitution of such non-foldable material as wood veneer, plywood and the like, and forming from these integrated unitary sheets or structures comprising fold or hinge-lines between the parts.

The essence of a collapsible container, it should be noted, is not so much that it be collapsible, as that it be so arranged that it may be shipped and stored in flat condition, and so that it may readily be erected into usable form without the necessity for tools or complicated operations.

Owing to present conditions, the supply of corrugated board has become seriously inadequate, and demand for collapsible files for both government and civil use is greatly expanding. Therefore, structures which are integrated and collapsible must be formed from other materials.

There are certain types of lumber which are still plentiful, such for instance as the so-called "egg crate veneer."

However, in the utilization of board or other stiff substitute materials of this type in the manufacture of collapsible containers, it becomes necessary to provide means which will securely integrate the walls of the container so that they are interconnected whether the container is collapsed or erected, while, at the same time, appropriate bend lines are provided so that the ultimate user may readily erect the container.

In the utilization of such board, various reinforcing and constructional elements may be utilized in the same manner as has previously been done in connection with corrugated board collapsible containers.

Thus, for instance, front and rear reinforcing

members, such as those shown in my Patent Numbers 2,118,011 and 2,159,070, may be placed on the container; roller mechanisms, such as those shown in, for instance, my Patent No. 2,233,906, may be utilized; and interlock members, such as shown in my Patent No. 2,245,026, may also be utilized.

In my application, Serial Number 21,411, there is also an indication of a manner in which fold lines may be provided, while at the same time, the container remains an integral unit, whether collapsed or erect. Essentially, such bend lines are formed by making the juncture between adjacent walls discontinuous and placing across this juncture a suitable connecting member such as a metallic strip. The bend line in the connecting strip, which is bendable, is determined by the discontinuous area in the adjacent walls. The area between adjacent walls need not necessarily be discontinuous. They may be weakened in any suitable manner to provide the same function of predetermining the bend line.

A primary object of the present invention, therefore, is the formation of collapsible containers having walls of relatively stiff material hingedly connected along fold lines by a connecting member.

While it is preferred that this reinforcing material be metal, it may be any other suitable bendable material.

Another object of the present invention is the provision of a collapsible container having adjacent walls of stiff material interconnected by flexible members.

These, and many other objects of my invention will become apparent in the following description and drawings, in which:

Figure 1 is a cross sectional view and showing an arrangement of the wall members of the file cabinet.

Figure 2 is a cross sectional view showing the container of Figure 1 in collapsed condition.

Figures 3, 4, 5, and 6 are fragmentary views in perspective showing various types of interconnecting and reinforcing members.

Figure 7 and 8 are cross sectional views showing the manner in which the reinforcing members of Figure 6 may be used.

Figure 9 is a cross sectional view of a three-sided container showing the arrangement of the reinforcing members for connecting the walls.

Figure 10 is a cross sectional view partly in perspective, showing the container of Figure 9 in collapsed condition.

In Figures 1 and 2 I have shown in erected

and collapsed condition a file casing or container in which the walls are of wood veneer and wherein staples may be used to effect the interconnection of the walls.

Referring to Figure 2, which shows the collapsed condition, walls 51a and 53a are connected by staples. The staple 100 has a main portion 101 which passes entirely through the wall 51a and along the edge 75a of wall 53a. The clinched-over legs 102 and 103 of the staple 100 pass once more through the walls 51a and 53a in the manner shown in Figure 2. Similar staples 100 are provided at the opposite end of the collapsed container, connecting walls 54a and 52a.

Similar staples or wires are used at the other joints. Thus, for instance, staple 105 has a main portion 106 which extends across the edge 107 of wall 51a and the edge 108 of wall 54a. A portion 109 of staple 105 is clinched over and caused to enter into the wall 51a, and a portion 110 of staple 105 is clinched over and caused to enter into the wall 54a; thus, the staple 105 is S-shaped, while the staple 100 is C-shaped. Again, similar staples 105 are used to connect the walls 51a and 52a.

When the container is unfolded, it unfolds to the position shown in Figure 1.

The bend lines are all predetermined by the fact that edges of the adjacent walls abut against medial portions of the staples 100 and 105; thus, definitely guiding and predetermining the bend lines in each staple.

The projection of wall 51a beyond wall 53a, and the projection of wall 52a beyond wall 54a predetermine the order of folding.

The casing, when erected, then has the form shown in Figure 1 where the staples 100 have been bent to the form shown in Figure 1, and the staples 105 have been bent to a true S-shaped form, shown in Figure 1.

Obviously, any type of connecting material may be used in exactly the same manner, with the order of unfolding of the container being predetermined by similar arrangements, and the fold or bend lines in the connecting or reinforcing members being predetermined either by appropriate spacing or weakening of adjacent walls to determine the bend line, or by arrangement of the adjacent walls to provide straight edges which determine the bend line.

Metal connecting strips may of course be used. While it is preferred that for simplicity in construction the strips have a simple form, various decorative forms may be utilized which will either conceal the slots from which the prongs are driven, or which may serve to further reinforce the strips themselves and to further predetermine the bend lines.

Thus, in Figure 3, I have shown a metallic connecting strip, 155a. Here, the metallic strip has exactly the same essential construction for connecting purposes, including the prongs 62 formed out of slots in the body of the metallic strip and with each row of prongs extending in opposite direction to be secured to adjacent walls. The slots from which each row of prongs has been driven are, however, covered by reentrant flanges 120 and 121 which are bent over to conceal them. The edges of these flanges assist in determining the bend line of the metallic strip, and at the same time provide for a decorative covering which conceals the slots.

Similarly, in Figure 4, I have shown a me- 75

tallic strip 155 in which each row of prongs 62, in this case, extends on the same side of the strip 155, and the reentrant flanges 123 and 124 serve to provide a decorative and reinforcing cover for the slots from which the prongs are driven. Again, the edges of these reentrant flanges may assist in determining the bend line.

In Figure 5, I have shown a modification of the constructions of Figures 3 or 4 wherein the basic strip 255 is provided with its prongs 62 and the covering strip or flange 224 is also provided with prongs 262 which are downwardly depressed and in face to face engagement with the prongs 62.

In order to ensure that these prongs may be close to each other and operate as a single reinforced prong, the slots 130, from which prong 62 is driven, may extend on one side of the line of prongs, and the slot 131, from which prong 262 is driven, may extend from the opposite side of the line of prongs. The two prongs 62 and 262 may then operate as a single unit.

The member 224 may be a reentrant flange on the main metallic strip 255, or the member 224 may be the main metallic strip, and the element 255 may be the reentrant flange.

In Figures 6 to 8 I have shown a metallic connecting strip 355 which is provided with a downwardly dependent prong 62 and with a downwardly dependent prong 362.

The lines of prongs 62 are to engage the wall 51, and the lines of prongs 362 are to engage the wall 53, as shown in Figure 7.

The strip 355 is provided with a reentrant flange 324 from which an additional line of prongs 325 are struck, these prongs 325 being struck out of slots 326.

The prongs 62 and 362 are pointed prong members which are utilized for securing purposes in the manner shown in Figure 7.

The prongs 325 cooperate with the additional flange 330 to form a spacing channel. That is, as shown in Figure 7, the walls 51 and 53 are spaced from each other by the space 63 which is equal in extent to the thickness of a wall. The flange 330 and the line of prongs 325 are spaced from each other by the thickness of a wall so that they may accurately space the wall members 51 and 53. The prongs 62 and 362 serve effectively to secure the walls 51 and 53 on opposite sides of the members 330 and 325.

An accurate folding line 67, in the member 355, is predetermined by reason of the fact that the double thickness of flange 324 terminates at the fold line 67 thus providing an additional stress differential which will ensure the accuracy of the fold line.

Since the fold line necessarily occurs at the area 67, then, when the walls 51 and 53 are bent with respect to each other, the members assume the form shown in Figure 8.

The external appearance of the metallic connecting member 355 is then the same as if a simple planar strip were used.

My invention is, of course, capable of many modifications and may be utilized not merely in file cabinets of the ordinary types, but may be utilized, for instance, in three-sided casings.

Thus, for instance, in Figures 9 and 10, I have shown a three-sided casing 200 having a top wall 201 and side walls 202 and 203.

The walls 203 and 201 are interconnected by metallic strip 60a.

A similar metallic strip 60a is used on the op-

posite side at the wall connection between walls 201 and 202.

The edge 205 of wall 203 is a predetermining factor which, upon rotation of walls 203 and 201 with respect to each other, will effectuate a bend of the strip 60a along a line coinciding with the edge 205. Similarly, the edge 206 of wall 202 predetermines the area of bend of the strip 60a when walls 202 and 201 are rotated with respect to each other.

Thus a simple three-sided casing of the form shown in Figures 9 and 10 may be formed.

Essentially, in the present invention, I have shown a means for utilizing relatively stiff material, preferably of a fibrous nature, in order to form collapsible containers.

For this purpose, I have shown means for utilizing reinforcing and connecting elements which have previously been found to be feasible and practical in the case of collapsible containers made of paper board or other rather flexible, fibrous materials.

In the present case, although, it is preferred that fibrous material be used as the construction lends itself to the utilization of material which is rather stiff and relatively inflexible. It makes possible the utilization of the cheapest kind of wood board as, for instance, the so called "egg crate veneer." It makes possible the creation of collapsible containers from relatively stiff material where the container may be shipped in collapsed form as an integral unit, and may merely be unfolded by the user in the same manner as was previously done in connection with other types of other collapsible containers made of flexible material.

While, for structural purposes, the connecting members may preferably be metallic, yet, as has been set forth, any material which is bendable or even flexible may be used for interconnecting the relatively stiff walls of the container.

In the foregoing, I have described merely representative embodiments of my invention. Many other forms in which my invention may be utilized should now be obvious to those skilled in the art. Accordingly, I prefer to be bound, not by the

specific disclosures herein, but only by the appended claims.

I claim:

1. A pair of panels extending in substantially the same plane, a hinged connection therefor; said panels being in spaced edge to edge relation, the space between adjacent edges being of the order of the thickness of one of said panels, said hinged connection comprising a strip extending longitudinally over the space between adjacent edges and secured by prongs struck therefrom at the adjacent margins of said panels; said panels being rotatable relative to each other, the line of bend in said metallic strip when said panels are rotated being determined by the spacing between said edges, said strip having a reentrant flange covering areas from which the prongs are struck.

2. A pair of panels extending in substantially the same plane, a hinged connection therefor; said panels being in spaced edge to edge relation, the space between adjacent edges being of the order of the thickness of one of said panels, said hinged connection comprising a strip extending longitudinally over the space between adjacent edges and secured at the adjacent margins of said panels; said panels being rotatable relative to each other, the line of bend in said metallic strip when said panels are rotated being determined by the spacing between said edges, and additional means carried by said strip for determining the bend line of said strip.

3. A pair of panels and a hinged connection therefor; said panels extending substantially in face to face relation, the registering adjacent edges of said panels being in stepped relation to each other, one edge of one panel being stepped inwardly from the adjacent edge of the other panel; said hinged connection comprising a wire stitch, secured to the outer surface of the one panel and passing across the edge thereof and secured to the inner surface of the other panel; said panels being rotatable to angular relation; said stitch being bendable, the bend in said stitch being determined by the edge of said one panel.

PHILIP ZALKIND.
